SHELF CLAMP

Charles A. Hollander, Evansville, Ind., assignor to
Servel, Inc., New York, N. Y., a corporation of
Delaware

Application May 8, 1934, Serial No. 724,544

1 Claim. (Cl. 248—250)

This invention relates to shelf clamps or retainers intended to be used in conjunction with supports for shelves or trays in refrigerators or other cabinets for maintaining the shelves in position.

The invention is intended to permit shipping of the shelves in place in the cabinet and eliminate the necessity of packing the shelves in a separate carton for shipment.

It is an object of the invention to provide a simple and inexpensive shelf securing clip for holding the shelves in place against vibration and during shipment, thus reducing the expense of additional crating and unpacking of the shelves.

Other objects and advantages will be apparent from the following description taken in connection with the accompanying drawing, wherein

Fig. 1 is a horizontal section through a cabinet showing a top plan view of a shelf held in position by spring clips in accordance with the present invention;

Fig. 2, a section on the line 2—2 of Fig. 1; and Fig. 3, a section on the line 3—3 of Fig. 1.

Referring to the drawing, a refrigerator cabinet 18 is provided with a porcelainized liner 11, and supports 12 carried by the liner for supporting a shelf 13. The shelf supports 12 are pegs or hooks of conventional construction each having an enlarged head, a threaded shank adjacent the head for reception of a nut thereon and with both a smooth shelf engaging portion and an upturned extremity disposed outwardly of the threaded portion of the shank. Each support 12 projects through an aperture in the liner and is fastened in position by means of the nut on the threaded shank engaging and bearing against a convex spring washer which preferably rests upon a gasket so that the liner will not be marred by the spring washer. The supports 12 are of sufficient length to permit the shelf to have a limited amount of lateral play or movement in order to compensate for inequalities in the liner caused by heat during the baking process. The shelf 13 has a tendency to vibrate or rattle due to this

lateral play if the cabinet is jarred as when not supported solidly or for any other reason. Spring clips 14 serve to prevent rattling of the shelf or dislodgment during shipment.

The clips 14 are each formed of spring metal, such as wire or the like. Each clip has an intermediate portion 15 for disposal beneath a support 12 and upwardly extending arms 16 and 17 forming a U-shaped portion. The arms 16 and 17 are bent substantially horizontally to overlie 10 the rim of the shelf. The arm 16 is curved downwardly to form a hook to fit over the rim or bounding frame of the shelf and the arm 17 is extended to underlie a flat ribbon which constitutes a cross-bar of the shelf. The free extremity of the arm 17 is provided with an upturned portion 18 for preventing disengagement of the arm 17 from the cross-bar which it underlies.

As shown, the shelf supports 12 are secured 20 two on the side walls and two on the rear walls of the cabinet. However, if desired they may be secured on the side walls or in any other manner preferred. Likewise the clips may be removed after shipment or left in place as desired. 25

It will be apparent to those skilled in the art that various other changes may be made in the construction and arrangement without departing from the spirit of the invention, and therefore the invention is not limited to that which is described in the specification and shown in the drawing, but only as indicated in the following claim.

What I claim is:

A clip for securing a wire grid refrigerator shelf upon a laterally extending supporting peg and comprising a resilient wire formed into a U-shaped portion for engagement beneath said peg and end portions extending laterally in the same direction from the legs of said U-shaped portion 40 for engagement above said shelf, one of said ends being long enough to be flexed beneath a part of said shelf to place the clip under tension.

CHARLES A. HOLLANDER.
